DESIGN FOR A COAT HANGER OR SIMILAR ARTICLE

Edward M. Paterson, Whittier, Calif., assignor to Plastic-Fibre Corporation, Whittier, Calif., a corporation

Application October 21, 1939, Serial No. 87,795

Term of patent 7 years

To all whom it may concern:

Be it known that I, Edward M. Paterson, a citizen of the United States, residing at Whittier, in the county of Los Angeles, State of California, have invented a new, original, and ornamental Design for a Coat Hanger or Similar Article, of which the following is a specification, reference being had to the accompanying drawing, forming a part thereof.

I claim:

The ornamental design for a coat hanger or similar article, as shown.

EDWARD M. PATERSON.
